PORTABLE SHOWER FACILITY OR THE LIKE

Joseph F. Dowd, P.O. Box 82, Hatch, N. Mex. 87937

Filed Feb. 23, 1971, Ser. No. 118,204

Term of patent 14 years

Int. Cl. D23—02

U.S. Cl. D23—49

FIG. 1

FIG. 2

FIG. 3

FIG. 4

FIG. 5

FIG. 6

FIG. 7

FIG. 8

FIG. 9

FIG. 1 is a top plan view of a portable shower facility or the like, in accordance with my new design;

FIG. 2 illustrates a front elevation of the invention illustrated in FIG. 1;

FIG. 3 is a front perspective view of the invention illustrated in FIG. 1;

FIG. 4 illustrates a sectional view taken on line 4—4 in FIG. 1 looking in the direction of the arrows;

FIG. 5 illustrates a sectional view taken on line 5—5 in FIG. 1 looking in the direction of the arrows;

FIG. 6 illustrates the sectional view taken on line 6—6 in FIG. 1 looking in the direction of the arrows;

FIG. 7 is a sectional view taken on line 7—7 in FIG. 1 looking in the direction of the arrows;

FIG. 8 is a sectional view taken on line 8—8 of FIG. 1 looking in the direction of the arrows; and

FIG. 9 illustrates a sectional view taken on line 9—9 in FIG. 1 looking in the direction of the arrows.

The characteristic features of my design reside in the interior of the portable shower facility or the like.

I claim:

The ornamental design for a portable shower facility or the like, substantially as shown and described.
